UNITED STATES PATENT OFFICE.

LERoy F. HINTZ, OF CHICAGO, ILLINOIS.

TOOL FOR TENSIONING AND TWISTING WIRES.

Application filed September 28, 1925. Serial No. 59,109.

This invention relates to a tool for twisting wires under tension, and has for its object to provide an apparatus which will be simple in construction, comparatively inexpensive to manufacture, and more efficient in use than those that have been heretofore proposed.

With these and other objects in view, the invention consists in the novel details of construction and combinations of parts more fully hereinafter disclosed and particularly pointed out in the claims.

Referring to the accompanying drawings, forming part of this specification, in which like numerals designate like parts in all the views:

Fig. 1 is a diagrammatic plan view showing how this tool is applied in use;

Fig. 2 is an enlarged side elevational view of a portion of the parts shown in Fig. 1;

Fig. 3 is an enlarged detail side elevational view partially in section showing a portion of the other side of the tool illustrated in Fig. 2;

Fig. 4 is a plan view partially in section of a portion of the parts shown in Fig. 2;

Fig. 5 is an end elevational view of the tool shown in Fig. 2;

Fig. 6 is a sectional view taken on the line 6—6 of Fig. 2, looking in the direction of the arrows;

Fig. 7 is a sectional view taken on the line 7—7 of Fig. 2, looking in the direction of the arrows; and

Fig. 8 is an elevational view of a portion of the parts shown in Fig. 2, illustrating the position of the wire after the twisting action has been accomplished.

In order that the precise invention may be the better understood, it is said: It is well known that there are a number of structures including building constructions, shipping containers, etc., where it is desired to firmly bind a plurality of parts together by means of a wire looped around said parts, and where the wire is placed under tension, the ends of the same are twisted together and then said ends are cut off so as to hold the parts together either permanently or

temporarily. The tool made the subject of this invention is adapted for all of these uses. As an example of a building construction, it might be pointed out that in making concrete walls, a framework such as is indicated by 1 in Fig. 1 is frequently formed and wherein the walls 2 and 3 are spaced apart by means of members 4, and said walls are braced by means of the uprights 5. In the space 6 thus produced, the concrete or other material is poured, and it is further well known that these walls such as 2 and 3 frequently show signs of giving away so that they have to be firmly secured together at least temporarily until the cementitious material sets. In the case just cited, it is common to pass a wire loop 7 through the walls 2 and 3 and sometimes around the uprights 5, as indicated, bringing both ends 8 and 9 of said loop 7 out on the same side of the structure, as illustrated in Fig. 1, whereupon said wire ends 8 and 9 are frequently twisted together by hand and then by means of various devices, not necessary to describe in detail, the middle portions or bights of the wire between the walls 2 and 3 are brought together, and in fact sometimes twisted together, in order to tighten the loop thus formed and to hold the walls 2 and 3 in place.

According to this invention, on the other hand, the loop is preferably formed as is illustrated in Fig. 1, and then the tool indicated generally by the numeral 10, is applied to the ends 8 and 9 of said loop, said ends are put under tension, are then twisted together and the ends cut off, all as will now be described.

That is to say, referring more particularly to Fig. 2, 11 indicates the main body portion of the general shape shown and which is preferably made out of sheet steel material. The twisting end of said portion 11 is provided with the cutaway slot 12 forming the two strip-like extending members 13 and 14; and formed on the member 13, and at right angles thereto, is the crescent-shaped member 15, while formed on the member 14 is a similar crescent-shaped member 16, as shown. Each of the members 15 and 16 are provided with the straight wall-like portions

17, and each of the crescent-shaped members 15 and 16 are provided with the curved portions 18, as illustrated. The curved portions 18 are so spaced apart and so shaped that 5 they form the approximately circular opening 19 at the center of the circular space occupied by the crescent members 15 and 16, and they also form the open curved slots 20, all as will be clear from Fig. 5. At a distance 10 from the extreme end members 15 and 16, the main body portion 11 is bent or dished as indicated at 21 and 22, and the dished portion is provided with the semicircular extension 23, as shown. Pivotaly mounted on each side of this dished extension are the wire tensioning disks 24 and 25, as will be 15 clear from Figs. 2 and 3. The tensioning disks 24 and 25 are provided with the radial slots 26 adapted to receive the ends of the wire, and one of said disks, as 25, for example, is provided with ratchet teeth 27 on its periphery engaged by a pawl 28 controlled by a spring 29. 30 represents an operating handle to which said pawl is pivoted, 20 as at 31, and said disks 24 and 25, as well as said handle 30, are secured to the main body portion 11 or to the extension 23 thereof by means of the common pivoting pin or short axle 33, as shown.

30 On the strip-like member 13 is rigidly secured the U-shaped member 34 which straddles said member 13, as best shown in Fig. 5, and opposite said member 34 is the U-shaped member 35 rigidly secured to the 35 strip-like member 14. To the rear of the slot 12 there is also secured to the main body portion 11 a U-shaped guide member having the parts 37 and 38 located on opposite sides of said main body portion 11, as will be 40 clear from Figs. 3 and 4. Said members 37 and 38 are so spaced from the U-shaped member 35 as to form a slot or guideway for the cutter members 39 and 40, with which the tool is provided. Said cutter members 45 are preferably two in number, as illustrated, and are pivoted as at 41 to the extreme end 42 of the cutter lever 43 pivoted to the guide members 37 and 38, as at 44. Said cutter lever 43 is bent as at 46 in a direction away 50 from the main body portion 11 in order that it may pass the dished portion 21, 22 of said main body portion, and it is again bent in an opposite direction as at 47, see Fig. 2, in order that its handle 48 may lie comparatively 55 close to the handle portion 49 of said main body portion 11.

50 represents a retainer latch secured to the main body portion 11, as at 51, which extends outwardly and downwardly from 60 said main body portion and terminates in a hook 54, see Fig. 3. Thus it will be seen that the latch member 50 not only serves as a guide to prevent the lever 43 from being bent inwardly so as to interfere with the 65 operation thereof, but the hooked end 54 of

the latch is adapted to receive and retain the member 43 in a position close to the main handle portion 49 so that the opening between the cutter 40 and its companion member 65 will permit the wire 8 to be threaded through the end of the device into the tensioning drum 25. In other words, the weight of the cutter actuating lever 43 would have a tendency to move the cutters 39 and 40 to such a position as to obstruct said opening unless said latch or hook 54 were employed. The extreme end of the main body portion 11 is provided with a pin 52 on which is swiveled the bearing member 53 so that the latter may turn independently of the said main body portion 11.

The ratchet teeth 27 of the disk 25 are also engaged by a dog 56 controlled by a spring 57, which dog is pivoted as at 58 to a plate-like member 59 secured to the extension 23 of the dished portion 21, 22 of the main body portion 11, as best shown in Figs. 3 and 4. The cutters 39 and 40 may be integrally or rigidly joined together as by means of the web member 60, see Figs. 3 and 6, so as to insure their rigidity and proper cutting action. The extreme end 42 of the cutting lever 43 is curved as at 61, so that when said lever is turned through a predetermined arc, said curved portion will 95 strike the surface 62, separating the two forked portions of the member 35, and thus limit the movement of the cutters 39 and 40, all as will be clear from Fig. 3.

The operation of this tool is as follows: 100 A loop of wire, such as 7, having been placed as indicated in Fig. 1 or around a plurality of any members that are to be readily and firmly joined together, the extreme end portions 8 and 9 of said wire are 105 introduced through the slots 20 between the crescent-shaped members 15 and 16, and are led to the disks 24 and 25, where the said wire ends 8 and 9 are passed through the slots 26 in said disk members and their 110 ends bent around the peripheries of said disks 24 and 25, all as will be clear from Figs. 2, 3 and 4. After the wires have been thus secured to the disks 24 and 25, a few motions may be had with the lever 30 115 in order to rotate said disks 24 and 25 with the aid of the pawl 28 on the said lever 30, whereupon the slack of said wires will be taken up, and the crescent-shaped disks 15 and 16 brought in close proximity to the 120 surface of the parts to be held together. When in this condition, the wires will be found to pass through the central circular opening 19 between the curved portions 18 of the crescent-shaped disk 15, and then the 125 handle 30 may be operated until the desired tension is had on said wires. When this tension is secured, the operator grasps the swiveled knob 53 in one hand, the tensioning lever 30 in the other hand, and rotates 130

said lever around the axis of the main frame 11 as a center, until the desired number of twists is placed in the wire ends. When the wires have been thus twisted, as indicated in Fig. 8, the operator, while still holding the swiveled knob 53 in one hand, transfers the other hand from the tensioning handle 30 to the handle 48 of the cutter actuating lever 43, unlatches said lever from its retaining hook 54, and moves said handle 48 away from the device thereby turning said lever about its pivot 44 and actuating the cutters 39 and 40 to sever the twisted wire against the edge 65 of the U-shaped member 34, all as will be clear from Figs. 2, 3 and 8.

It will be observed that the ends of the wire are disposed alongside of each other, and both extend into the opening in the end of the tool in the same direction. It will also be seen that these two free ends of the wire are spirally twisted together, and that after being spirally twisted together, both terminal ends are severed by the cutters. It will also be seen that the extent or length of the spirally twisted portion is limited by the length of the slot 12. That is to say, the number of twists imparted to the wire ends in twisting them together is limited to the length of the slot 12, within which the twists are formed. This is an important feature of the tool, as thereby the danger of over-twisting, and hence of thereby breaking the wire, is avoided.

35 What is claimed is:—

1. In a wire tensioning and twisting tool, the combination of an elongated main body portion, means at one end of the main body portion for receiving the free ends of a wire to be joined together, with said ends disposed side by side and extending in the same direction, means for tensioning said wires, means at the other end of said body portion to facilitate the turning of said body portion so as to twist together and tension said wires, and a cutter to sever said wires.

2. In a wire tensioning and twisting tool, the combination of an elongated main body portion, slotted means for receiving wires to be joined together at one end of said main body portion, rotatively actuated means including a pawl and ratchet for tensioning said wires, means at the other end of said body portion to facilitate the turning of said body portion so as to twist together said wires, and a reciprocating cutter to sever said wires.

3. In a tool adapted to twist a pair of wire ends together, the combination of an elongated body portion capable of being axially rotated on its longer axis to spirally twist wire ends together, slotted means located at one end of said body portion to receive the wire ends to be twisted, rotatable tensioning

means carried by said body portion to tension said wire before the ends thereof are twisted, and a reciprocating cutting means for severing both of said wire ends after they are twisted together. 70

4. In a tool adapted to twist a pair of wire ends together, the combination of an elongated body portion capable of being axially rotated on its longer axis to spirally twist wires together, curved slotted means located 75 at one end of said body portion to receive both wire ends to be twisted, rotatable tensioning means including a pawl and ratchet and an operating lever carried by said body portion to tension each of said wire ends 80 before they are twisted, and a reciprocating cutting means including a lever for severing both of said wire ends after they are twisted together.

5. In a tool adapted to twist together a pair of wire ends, the combination of an elongated main body portion adapted to be turned on its longer axis to twist a pair of wires together, a slotted member for receiving said wires before the twisting operation 90 and to hold said wires during said operation, a wire tensioning means carried by said body portion, and a positively actuated reciprocating pair of cutters for serving said wires also carried by said body portion. 95

6. A tool of the character described provided with an elongated body portion having a slotted end for the reception of wires to be twisted, a reciprocating cutter mounted on said end, a cutting lever pivoted on said end, 100 and a rotating wire tensioning means mounted adjacent said end.

7. A tool of the character described provided with an elongated flat body portion having a slotted end for the reception of 105 wires to be twisted, a reciprocating cutter and associated parts mounted on said end, a cutting lever pivoted on said end adjacent said cutter, and a rotating wire tensioning means including an operating lever mounted 110 adjacent said end.

8. A tool of the character described, provided with an axially rotatable body portion, said body portion having a slot to receive two wire ends to be spirally twisted together by the axial rotation of said body portion, the number of spiral twists being determined by the length of said slot, means for tensioning the wire, and means to sever the terminals of said wire ends after twisting them together. 115

9. A tool of the character described provided with a body portion slotted at its end for the reception longitudinally therethrough of two wire end portions disposed side by side therein, said body portion being axially rotatable, a tensioning means to receive each wire end portion, and a wire cutting device to sever both wire end portions. 125

10. A tool of the character described pro-

- vided with a body portion, tensioning means carried by said body portion, said body portion being provided with a slot at its end longitudinally through which two wire end portions are adapted to pass to said tensioning means, said body portion adapted to be axially rotated to twist together the wire

end portions within said slot, and severing means disposed intermediate said slot and tensioning means to sever both wire end portions.

In testimony whereof I affix my signature.

LEROY F. HINTZ.
